ROLLER CUTTER MOUNTING

Alfred C. Catland, Alhambra, and Philip C. Efronson, Whittier, Calif., assignors to Globe Oil Tools Company, Los Nietos, Calif., a corporation of California

Application November 17, 1936, Serial No. 111,182

10 Claims. (Cl. 255—72)

This invention relates to well drilling tools and relates more particularly to the roller cutter mountings of a well drill. A general object of this invention is to provide practical and dependable anti-friction bearings or mountings for the roller cutters of a well drill.

Another object of this invention is to provide a rotary well drill embodying a ball bearing mounting for a roller cutter in which the balls assume the end thrusts in both directions as well as the radial thrusts.

Another object of this invention is to provide a ball bearing mounting for a roller cutter in which all of the thrusts are transmitted through the balls and the races of the cutter bushing and pin so that the body of the drill is not subjected to wear due to rotation of the cutter.

Another object of this invention is to provide an anti-friction ball bearing mounting of the character mentioned that is small and very compact and therefore particularly adapted for mounting a roller cutter of a core drill.

Another object of the invention is to provide an anti-friction cutter mounting of the character mentioned that is long wearing to maintain the cutter in the operative position for a long period of use so that the cutter maintains the drill to gage.

Another object of the invention is to provide a cutter mounting of the character mentioned in which the end race or the thrust bushing is rigidly secured to the body of the drill, thereby preventing chattering of the bearing parts.

The various objects and features of our invention will be fully understood from the following detailed description of a typical preferred form and application of our invention, throughout which description reference is made to the accompanying drawing, in which:

Fig. 1 is a side elevation of a core drill embodying the present invention with a portion broken away to illustrate the cutters and their mountings in vertical cross-section. Fig. 2 is an enlarged fragmentary vertical sectional view illustrating one of the outer cutters and its mounting. Fig. 3 is a view similar to Fig. 2 illustrating one of the inner cutters and its mounting and Fig. 4 is a fragmentary sectional view taken as indicated by line 4—4 on Fig. 2.

The cutter mountings of the present invention are adapted to be embodied in rock drills as well as rock core drills. Due to the fact that they are small and compact the mountings are particularly well adapted for embodiment in roller rock core drills. Accordingly, we will describe the cutter

mountings of the present invention embodied in a rock core drill, it being understood that the invention is not to be construed as limited to the specific form or application about to be described.

The core drill illustrated in the drawing includes an outer barrel 10 to be connected with a rotary well drill string. A tubular bit head 11 is connected with the lower end of the barrel 10 through the medium of a sub 12. The head 11 has a central vertical opening 13 to pass the core and an inner barrel 14 is provided within the outer barrel 10 to receive the core. Circumferentially spaced sockets or recesses 15 and 16 are provided in the lower end of the head 11 to receive the roller cutters. The inner and outer walls 17 and 18 of the recesses 15 are inclined downwardly and outwardly relative to the vertical axis of the tool. The inner and outer walls 19 and 20 of the recesses 16 are inclined downwardly and inwardly with respect to the vertical axis of the drill. Bearing surfaces 21 are provided on the outer walls 18 of the recesses 15 and similar raised surfaces 22 are provided on the inner walls 19 of the recesses 16. Fluid ports 23 and 24 are provided in the head 11 to communicate with the upper ends of the recesses 15 and 16 respectively, to effect the flushing of the cutters. It is to be understood that the head may have one or more cutter receiving recesses 15 and 16.

The present invention includes a cutter 25 for operation in each recess 15, a pin 26 passing through the cutter 25, a washer or bushing 27 on the pin 26 and series of balls 28 and 29 cooperating with races in the pin 26, the bushing 27 and the cutter 25.

The cutter 25 is a frusto-conical roller cutter intended to rotate about a downwardly and inwardly inclined axis. The cutter 25 is rotatably mounted in its recess 15 to act on the outer portion of the well bore and cut the bore to gage. The pitched or conical periphery of the cutter 25 is provided with suitable cutting teeth 30. In the structure illustrated the teeth 30 are straight and axial. The outer corners of the teeth 30 are bevelled away to act on the vertical side wall of the well bore. The opposite ends of the cutter 25 may be flat and normal to its axis. The cutter 25 is provided with a central longitudinal opening 31 to receive the pin 26 and the other bearing parts. The opening 31 is generally cylindrical and is provided intermediate its ends with a restriction or flange 32. The inner side of the flange 32 is spherically concaved to constitute a ball race 33. The outer side of the flange 32 is spherically concaved to form an outer ball race 34. The race 34

has a larger radius of curvature than the race 33 and the opening 34 is larger in diameter at its outer portion, as clearly illustrated in the drawing. The races 33 and 34 are positioned to face 5 toward the adjacent ends of the cutter and diagonally relative to the longitudinal axis of the cutter.

The shaft or pin 26 passes through the opening 31 of the cutter 25 and is carried by the head 11 to rotatably support the cutter 25. The supporting pin 26 is passed outwardly through a downwardly and inwardly inclined opening 36 in the inner wall of the head 11 to extend outwardly through the recess 15 and the outer portion of the pin is threaded in a correspondingly inclined opening 36 in the outer wall portion of the head. A head 37 is provided on the inner end of the pin 26 and is suitably recessed in the inner end of the opening 35. A part of the head 37 is peened into a notch 38 to prevent unthreading of the pin. In accordance with the invention the pin 26 is graduated in diameter to have two outwardly facing annular shoulders 39 and 40. The shoulder 39 may be flat and normal with respect to the longitudinal axis of the pin. The inner shoulder 25 40 is in the nature of a ball race and is spherically concaved. The shoulder or race 40 is spaced slightly inwardly from the race 33 so that a line drawn through the centers of the opposing races 33 and 40 is pitched with respect to the longitudinal axis of the pin 26.

The washer or bushing 27 surrounds the pin 26 and bears against the bearing surface 21 on the outer wall 18 of the recess 15. The inner end of the bushing 27 is engaged by the shoulder 39 which clamps the bushing against the surface 21. In accordance with the invention a flat sided key or rib 41 is provided on the surface 21 and is received in a correspondingly shaped groove 42 in the bushing 27 to prevent rotation of the bushing. The washer or bushing 27 may be welded to the head 11 at the lower end of the surface 21 as indicated at 43 to positively hold the bushing against movement with respect to the head. The welding at 43 may also transmit some of the upward strains from the washer to the head 11. The washer or bushing 27 is received in the outer portion of the cutter opening 31. A spherically concaved annular race 44 is provided in the inner end or corner of the bushing 27. The race 44 opposes the race 34 in the interior of the cutter 25 and is located so that a line drawn through the centers of the two races is pitched with respect to the longitudinal axis of the pin 26.

The series of balls 28 cooperates with the opposing races 33 and 40 and the series of balls 29 cooperates with the races 34 and 44 to rotatably support the roller cutter 25. The balls 28 and 29 are arranged in annular series to surround the pin 26 and the inner end portion of the washer or bushing 27. The outer series of balls 29 takes the principal end thrusts as well as some of the radial thrusts and therefore the balls 29 are larger in diameter than the balls 28. The races 33 and 40 are shaped and proportioned to properly cooperate with the balls 29 to rotatably support the inner end portion of the cutter 25, while the races 34 and 44 are formed and proportioned to cooperate with the balls 29 so that they rotatably support the outer end portion of the cutter. It will be observed that the series of balls 28 and 29 constitute the sole means for rotatably carrying or supporting the cutter 25. It is an important feature of the invention that the balls 28 assume the radial thrusts as well as the inward thrusts or thrusts toward the center of the head 11 while

the balls 29 assume the radial thrusts as well as the outward and the end thrusts. Accordingly, the two series of balls 28 and 29 receive all of the operating thrusts imposed on the cutter 25 relieving the head 11 of all wear due to rotation of the cutter. A washer 45 may be arranged between the inner end of the cutter 25 and the inner wall 17 of the recess 15, spacing the cutter from the inner wall of the recess. The washer 45 may be welded to the head 11 at 46 to prevent it from turning.

It will be noted that the cutter 25 rotatably supported as just described may freely rotate during operation with a minimum of friction. The bearing means mounting the cutter 25 is such that the cutter is prevented from shifting or wobbling and the cutter is definitely retained in position to cut the well bore to gage. The balls 28 and 29 which serve to rotatably support the cutter 25 on the pin 26 and the bushing 27 are very long wearing so that the cutter is rotatably supported in the proper manner for a long period of operation. The series of balls 28 and 29 assume the end thrusts from the cutter in both directions as well as the radial thrusts and the ends of the cutter do not bear on any parts of the head 11 or on the washer 45 for the transmission of the end thrusts. This, of course, relieves the head 11 of excessive wear and greatly simplifies the construction. The inner series of balls 28 cooperates with the race 40 on the pin 26, making the cutter mounting very compact. Being small and compact, the cutter mounting is particularly adapted to mounting the roller cutters of a core drill.

The cutter mounting of the present invention illustrated in Fig. 3 rotatably supports an inner cutter 50 in one of the recesses 16 of the drill head 11. The structure illustrated in Fig. 3 includes, generally, the cutter 50, a pin 51 passing through the cutter 50, a washer or bushing 52 on the pin 51 and series of balls 53 and 54 cooperating with the interior of the cutter 50 and with the pin 51 and the bushing 52 to rotatably support the cutter.

The cutter 50 is an inner cutter for acting on the formation at the bottom of the well bore and for cutting the core to size. The cutter 50 is substantially cylindrical and has flat parallel ends. A central longitudinal opening 55 extends through the cutter 50 from one end to the other. Peripheral cutting teeth 56 are provided on the cutter 50. The teeth 56 may be straight and axial and their ends or corners may be bevelled off as illustrated. A restriction or flange 57 is provided on the wall of the opening 55 between its ends. The outer side of the flange 57 is spherically concaved to form a ball race 58. The inner side of the flange 57 is spherically concaved in a like manner to constitute an annular ball race 59. The cutter opening 55 is somewhat enlarged in diameter at its inner portion to receive the bushing 52. The ball races 58 and 59 provided on the sides of the flange 57 face inwardly toward the longitudinal center of the cutter 50 and toward the adjacent ends of the cutter.

The pin 51 is similar, generally, to the above described pin 26. The pin 51 is passed inwardly through a downwardly and outwardly inclined opening 60 in the outer wall portion of the head 11 and extends inwardly to pass through the opening 55 of the cutter 50. The inner part of the pin 51 is threaded in a downwardly and outwardly inclined opening 61 in the inner wall part of the head 11. A suitable head 62 is provided on the outer end of the pin 51 and is recessed in the outer end of the opening 60. The head 62

may have a part peened over into a notch 62 in the exterior of the drill head 11 to prevent unthreading of the pin 51. In accordance with the invention the pin 51 is graduated in diameter to have two inwardly facing annular shoulders 63 and 64. The shoulder 63 may be flat and normal to the axis of the pin 51, while the shoulder 64 is spherically concaved to constitute a ball bearing race. The race 64 opposes the race 58 10 on the interior of the cutter 50 and is spaced some distance outwardly from the race 58 so that a line drawn through the centers of the two races is pitched or diagonal relative to the longitudinal axis of the pin 51.

15 The washer or bushing 52 is arranged on the pin 51 within the cutter 50 to engage against the bearing surface 22. The bushing 52 is provided with a groove 42^a similar to the above described groove 42 to receive a key or rib 41^a on the surface 22 which prevents rotation of the bushing. Welding 65 may secure the bushing 52 to the inner wall part of the head 11 to positively prevent movement of the bushing. An indented spherically concaved ball race 66 is provided in 20 the inner end of the bushing 52 to oppose the race 59 on the interior of the cutter 50. The race 66 is located some distance inwardly from the race 59 so that a line drawn through the centers of the two races is pitched or diagonal 25 with respect to the longitudinal axis of the pin 51.

30 The series of balls 53 and 54 cooperate with the pairs of opposed races 58 and 64 and 59 and 66, respectively to rotatably support the cutter 50. The balls 53 and 54 are arranged in annular series 35 to surround the pin 51 and the washer 52 respectively. Due to the above described relationship between the races 58 and 64 the balls 53 are operable to receive the end thrusts from the cutter 50 in an outward direction or a direction 40 away from the vertical center of the drill. In a like manner the races 59 and 66 are positioned and related so that the balls 54 assume the inward end thrusts, that is, the thrusts on the cutter 50 directed inwardly toward the vertical center 45 of the drill. It is to be understood, of course, that the series of balls 53 and 54 also assume the radial thrusts on the cutter 50. Thus the two series of balls 53 and 54 operate to transmit or assume the end thrusts in both directions 50 as well as the radial thrusts imposed on the cutter 50. A washer 68 may be arranged on the pin 51 to space the outer end of the cutter 50 from the bearing surface 20. The series of balls 53 and 54 take on the end thrusts imposed on the cutter 50 and washer 68 does not transmit any thrusts from the cutter to the surface 20. Welding 69 may secure the washer 68 to the outer wall part of the drill head 11 to prevent undesirable movement of the washer.

55 It is believed that the operation of the structure illustrated in Fig. 3 will be readily apparent from the foregoing detailed description. The cutter 50 is supported by the spaced series of balls 53 and 54 so that it is free to rotate with a minimum of friction. The balls 53 and 54 assume or transmit the end thrusts imposed on the cutter, relieving the head 11 and the other parts of the bearing from wear due to such thrusts. 60 One series of balls 53 directly cooperates with the race 64 on the pin 51 while the other series of balls 54 cooperates with the bushing 52 on the reduced part of the pin so that the bearing or mounting is very small or compact. The mounting is dependable and long wearing and is oper-

able to support the cutter 50 in the proper position for a long period of operation.

Having described only a typical preferred form and application of our invention we do not wish to be limited or restricted to the specific details set forth, but wish to reserve to ourselves any variations or modifications that may appear to those skilled in the art or may fall within the scope of the following claims:

Having described our invention, we claim:

1. In a well drill, a body having spaced supports, a roller cutter between the supports and having an opening, axially spaced ball races on the interior of the cutter, a pin carried by the supports and passing through the opening, a ball race formed in the pin and opposing one of the first mentioned races, balls cooperating with the opposing races, the said opposing races being related so that a line passing through the points of contact of a ball with the races is pitched relative to the axis of the cutter whereby the balls assume the end thrusts toward one end of the cutter as well as the radial thrusts, a part on the pin, a ball race formed in said part and opposing the other of said first mentioned races, and balls cooperating with the last mentioned opposing races, the said last mentioned opposing races being related so that a line passing through the points of contact of a ball with them is pitched relative to the axis of the cutter whereby the last mentioned balls assume the end thrusts toward the other end of the cutter as well as the radial thrusts.

2. In a well drill, a body having spaced supports, a roller cutter between the supports and having an opening, a pin carried by the supports and passing through the cutter, a shoulder on the pin forming a ball race within one end portion of the cutter, a ball race on the interior of the cutter opposing the first mentioned race, a series of balls cooperating with the races to rotatably support said end portion of the cutter, the races being related so that a line passing through the points of contact of a ball with the races is pitched relative to the axis of rotation of the cutter whereby said balls assume the radial thrusts and the end thrusts toward the adjacent end of the cutter, and means rotatably supporting the other end portion of the cutter, said means including a bushing on the pin and a series of balls cooperating with the bushing and the interior of the cutter.

3. In a rotary well drill, spaced supports, a roller cutter arranged between said supports, the cutter having a longitudinal opening, axially spaced ball races on the interior of the cutter facing inwardly and toward the adjacent ends of the cutter, a pin carried by the supports and extending through said opening, a ball race on the pin opposing one of the first mentioned races, a series of balls cooperating with the race on the pin and the said first mentioned race, a shoulder on the pin, a bushing on the pin between said shoulder and one of said supports, a race on the bushing opposing the other first mentioned race, and a series of balls cooperating with the race on the bushing and the said other first mentioned race.

4. In a rotary well drill, spaced supports, a roller cutter arranged between said supports, the cutter having a longitudinal opening, axially spaced ball races on the interior of the cutter facing inwardly and toward the adjacent ends of the cutter, a pin carried by the supports and extending through said opening, a ball race on

- the pin opposing one of the first mentioned races, a series of balls cooperating with the race on the pin and the said first mentioned race, a shoulder on the pin, a bushing on the pin held against the adjacent support by said shoulder, a race on the bushing opposing the other first mentioned race, and a series of balls cooperating with the race on the bushing and the said other first mentioned race.
5. In a rotary well drill, spaced supports, a roller cutter arranged between said supports, the cutter having a longitudinal opening, axially spaced ball races on the interior of the cutter facing inwardly and toward the adjacent ends of the cutter, a pin carried by the supports and extending through said opening, a ball race on the pin opposing one of the first mentioned races, a series of balls cooperating with the race on the pin and the said first mentioned race, a shoulder on the pin, a bushing on the pin held against the adjacent support by said shoulder, means holding the bushing against rotation, a race on the bushing opposing the other first mentioned race, and a series of balls cooperating with the race on the bushing and the said other first mentioned race.
10. 6. In a rotary well drill, spaced supports, a roller cutter arranged between said supports, the cutter having a longitudinal opening, axially spaced ball races on the interior of the cutter facing inwardly and toward the adjacent ends of the cutter, a pin carried by the supports and extending through said opening, a ball race on the pin opposing one of the first mentioned races, a series of balls cooperating with the race on the pin and the said first mentioned race, a shoulder on the pin, a bushing on the pin held against the adjacent support by said shoulder, means holding the bushing against rotation, a race on the bushing opposing the other first mentioned race, and a series of balls cooperating with the race on the bushing and the said other first mentioned race.
15. 7. In a rotary well drill, spaced supports, a roller cutter arranged between said supports, the cutter having a longitudinal opening, axially spaced ball races on the interior of the cutter facing inwardly and toward the adjacent ends of the cutter, a pin carried by the supports and extending through said opening, a ball race on the pin opposing one of the first mentioned races, a series of balls cooperating with the race on the pin and the said first mentioned race, a shoulder on the pin, a bushing on the pin held against the adjacent support by said shoulder, means holding the bushing against rotation, a race on the bushing opposing the other first mentioned race, and a series of balls cooperating with the race on the bushing and the said other first mentioned race.
20. 8. In a well drilling tool, a body having spaced supports, a cutter having an opening, ball races in the wall of the opening, a pin extending between the supports and passing through the opening, a ball race on the pin opposing one of the first mentioned races, a bushing on the pin, a ball race on the bushing opposing the other of the first mentioned races, and balls cooperating with the pairs of opposing races forming the sole means for rotatably supporting the cutter.
25. 9. In a well drilling tool, a body having spaced supports, a cutter having an opening, a pin extending between the supports and passing through the opening, ball bearings means in the opening rotatably supporting the cutter on the pin, said means including a bearing member on the pin having a ball race, and balls cooperating with the ball race, and the cutter, and a weld securing said member to one of the supports.
30. 10. In a well drilling tool, a body having spaced supports, a cutter having an opening, a pin extending between the supports and passing through the opening, ball bearing means in the opening rotatably supporting the cutter on the pin, said means including a bearing member on the pin having a ball race, and balls cooperating with the ball race and the cutter, a weld securing said member to one of the supports, a washer at an end of the cutter and a weld securing the washer to the other support.
35. 11. In a well drilling tool, a body having spaced supports, a cutter having an opening, a pin extending between the supports and passing through the opening, ball bearing means in the opening rotatably supporting the cutter on the pin, said means including a bearing member on the pin having a ball race, and balls cooperating with the ball race and the cutter, a weld securing said member to one of the supports, a washer at an end of the cutter and a weld securing the washer to the other support.
40. 12. In a well drilling tool, a body having spaced supports, a cutter having an opening, a pin extending between the supports and passing through the opening, ball bearing means in the opening rotatably supporting the cutter on the pin, said means including a bearing member on the pin having a ball race, and balls cooperating with the ball race and the cutter, a weld securing said member to one of the supports, a washer at an end of the cutter and a weld securing the washer to the other support.
45. 13. In a well drilling tool, a body having spaced supports, a cutter having an opening, a pin extending between the supports and passing through the opening, ball bearing means in the opening rotatably supporting the cutter on the pin, said means including a bearing member on the pin having a ball race, and balls cooperating with the ball race and the cutter, a weld securing said member to one of the supports, a washer at an end of the cutter and a weld securing the washer to the other support.

ALFRED C. CATLAND.
PHILIP C. EFROMSON.
